MANUFACTURED ARTICLE OF FURNITURE

Clinton L. Stevens, Jamestown, N. Y.

Application April 19, 1944, Serial No. 531,728

7 Claims. (Cl. 5—286)

1

This invention relates to an improvement in manufactured articles of furniture, and more particularly to individual parts thereof.

More specifically the invention pertains to manufactured parts that comprise and are assembled into articles of furniture, and for a fuller understanding of its purpose, the invention is embodied in a supporting rail, such, for example, as the side rail of a bedstead.

For some time in the past it has been common practice to manufacture comparatively thin sheets from cellulose fiber to provide rough or finished covering for walls and the like. These sheets are commercially available in varying thicknesses; the thicker sheets being more porous and usually serving as an insulating board, and the thinner sheets, being more highly compressed and dense, serving as a finishing board. So far as is known, no effort has been made to provide a bond for the cellulose fibers of a wall board to give it strength beyond that required in the erection of walls or partitions. In other words, wall board manufactured from cellulose fibers has been entirely in sheet form and without structural design by which to give such strength as to render it capable of serving to support a weight other than its own. It is a purpose of the present invention to illustrate and describe one of several uses to which pressed, properly bonded, cellulose fibers may be put when designed to give structural strength that heretofore was provided through the use of additional structural members formed from wood or metal.

In the present illustrated form, the invention is directed to a side rail of a bedstead. This rail consists of cellulose fibers held together in compressed relationship with a binder that is of such nature as to give added strength to the fibers, such a binder being available in several of the commercial synthetic resins. The advantages of a structural member of this nature are many; namely, the utilization of a material or substance that is largely waste, and with a suitable bonding agent, molding this material into the form of parts of an article of furniture. Thus, although the parts of the article are molded, they, nevertheless, being formed from wood fibers, will have the general appearance of wood, as well as its warmth, as distinguished from metal. Additionally, by molding such parts, the manufacturer is limited in design or pattern only to the extent of the design of the mold, and even this design may be altered by further work, following removal from the mold. Thus, for example, a rail may be produced in a mold of given contour and may

2

be subsequently ornamented, painted, or veneered to simulate any desired material or color. The rail is so constructed as to provide adequate strength and at the same time is of considerably less weight than its currently manufactured counterpart in either wood or metal.

Other objects and advantages of the invention will become apparent from a consideration of the following specification, taken in conjunction with the accompanying drawing, wherein one application of use of the invention is shown; and in which

Fig. 1 is a fragmentary perspective view of one end of a bed rail embodying the invention, parts being broken away to disclose the method of anchoring a bed hook thereto;

Fig. 2 is a vertical sectional view taken substantially on the line 2—2 of Fig. 1;

Fig. 3 is a further vertical sectional view similar to Fig. 2, showing the application of a veneer or other finishing material to the side and top surfaces of a rail;

Fig. 4 is a vertical sectional view taken substantially on the line 4—4 of Fig. 1 and shows one form of reinforcement that may be embedded in the rail ribs to give added strength;

Fig. 5 is a fragmentary side elevational view of the rail shown in Fig. 1, parts being broken away to disclose a form of reinforcement applicable to the web portion of the rail; and

Fig. 6 is a vertical sectional view taken substantially on the line 6—6 of Fig. 5 and shows a further reinforcement for the rib, together with the location of the web reinforcement.

Referring more particularly to the drawing, the reference numeral 10 is employed to generally designate the side rail of a bed in which is embodied one form of the invention. This rail is formed from suitably bonded cellulose fibers, being made into rail form in a mold under application of heat and pressure. The rail comprises a vertical web portion 11 which is located towards the outer or exposed side, and this web portion connects, and is, of course, integral with top and bottom ledges 12 and 13. As illustrated in Fig. 2 of the drawing, the rail has the appearance of a channel, and it is proposed, in order to give necessary structural support to the top and bottom ledges 12 and 13, that the ends 14 be the full rail depth. Intermediate the ends 14, a suitable number of ribs 16 are provided. These ribs are, of course, integral not only with the web portion 11, but with the top and bottom ledges 12 and 13 as well, and they serve, when provided in suitable number, to give such support to the top ledge

12 that it may be readily used to support a spring. Additionally, the ribs 16 give such added strength to the lower ledge 13 that it may be utilized as a support for the ends of cross-slats which, in certain types of beds, serve to mount a spring.

End plates 17 are embedded in and secured to the rail ends 14 during the molding operation. These plates may be notched in one or more places, as indicated at 18, for the purpose of anchoring them and preventing their subsequent dislodgment from the rail ends. Each plate is also formed with one or more hooks 19 and inclined slots 21 by which to secure the rail end to the head or foot-board of a bedstead. The particular type of hook 19 forms no part of the invention.

It is contemplated that certain types of articles of furniture are subjected to greater structural strain than are other articles, and in the present illustration it would be true that the rails of single beds would normally be required to stand up under a lesser weight than would the rails of a three-quarter or double bed. Under such circumstances, it is contemplated to provide a structural reinforcement in the rail at such points, or throughout its length, as may be found necessary to give added strength. In Fig. 4 of the drawing a metal rod or wire 22 is shown. This wire is intended to give reinforcement to the rib 16 and is of such proportions and shape as to act as a tie between the ledges 12 and 13 and the rib 16. Additionally, it is contemplated to provide reinforcement for the web 11, and one form of such reinforcement is shown in Fig. 5 of the drawing, wherein permanently secured, vertical and horizontal wire rods 23 and 24 are utilized. The number of such rods may be increased over that shown, and it is contemplated, in lieu of the use of such rods, to utilize expanded sheet metal. With use of rods as a reinforcement it is possible to continue them, as illustrated in Fig. 6 of the drawing, at the webs to provide horizontal and vertical parts 26 and 27. In this instance, the parts 26 and 27 take the place of the rods 22, illustrated in Fig. 4. The metal reinforcement in either the rib 16 or web 11, or both, is such as to add only immaterially to the weight of the rail, and since it is completely embedded, presents no unsightly appearance.

As is suggested in Figs. 3 and 4 of the drawing, the rail, along its web 11 and top ledge 12, may be covered with a veneer that will match the material from which a head and foot-board are constructed. The application of the veneer is a simple matter and its permanency is assured, since it is applied to like material.

Although applicant has shown and described only one part of a given article of furniture that may be constructed in accordance with the invention, and in such part has shown only one form of reinforcement, it will be apparent to those skilled in the art that the invention is applicable to the manufacture of parts of other articles of furniture in the manner taught herein and such application or modification thereof is therefore contemplated insofar as it is within the spirit and scope of the invention as set out in the annexed claims.

Having thus set forth my invention what I claim as new and for which I desire protection by Letters Patent is:

1. In an article of furniture, a support member comprising a web portion, like ledges terminat-

ing opposite edges of said portion, full depth end portions on said member, a plate partially embedded in each of said end portions and having hook elements extending therebeyond, intermediate ribs connecting the ledges of said member, said ribs, ledges and web portion being integral and said ribs serving to rigidify said ledges.

2. In an article of furniture, a channel-like support member comprising a web portion, integral top and bottom ledges terminating opposite edges of said portion, end portions substantially the full depth and height of said member, hook plates having their ends embedded in said end portions, a plurality of ribs intermediate the end portions, each of said ribs being integral with said web and the top and bottom ledges and terminating substantially flush with the ledges.

3. In an article of furniture, a support member having solid ends, hook plates having their ends permanently joined to said solid ends, said member, intermediate its ends, being channel-like in cross section, the sides of the channel constituting top and bottom ledges, a plurality of spaced ribs formed integral with said ledges and the connecting web of the channel, each of said ribs, in cross section, being wedge-shaped with the wider part at the web of the channel and the narrow edge terminating substantially flush with the free edges of the top and bottom ledges.

4. A support member comprising a web portion, corresponding right angle flanges terminating opposite edges of said web portion and cooperating therewith to form a channel, solid ends on said channel, hook plates having their ends permanently joined to the solid ends, a plurality of spaced apart ribs formed integral with the web and flanges, each of said ribs having an edge terminating within the limits of said channel, and means forming a part of each of said ribs serving to reinforce the integral connection with said flanges.

5. In an article of furniture, a channel-like support member comprising a web portion, integral top and bottom ledges terminating opposite edges of said portion, at least one end of said member being solid, an attachment element extending in the direction of the length of said member, said element having a portion embedded in said solid end, and a further portion extending therebeyond and providing fastening means for said member to another element of the article of furniture.

6. In an article of furniture, a channel-like support member comprising a web portion, integral top and bottom flanges terminating opposite edges of said web portion, a hook plate extending in the direction of the length of said member, an end of said channel-like member being solid and of a thickness and length to receive and embed an end portion of said hook plate, and means forming a part of the embedded portion adapted to anchor said hook plate to said solid end.

7. In an article of furniture, a channel-like support member comprising a web portion, integral top and bottom ledges terminating opposite edges of said support, solid end portions on said member, hook plates having their ends embedded in said end portions, at least one rib intermediate the solid end portions, said rib being made integral with said web and the top and bottom ledges and terminating substantially flush with at least one of the ledges.

CLINTON L. STEVENS.
